(**) Term: **14 Years**

(57) **CLAIM**

(21) Appl. No.: **29/176,387**

The ornamental design for an articulated gap cover for pickup tailgate, as shown and described.

(22) Filed: **Feb. 24, 2003**

DESCRIPTION

(51) LOC (7) Cl. **12-16**

FIG. 1 is a perspective view of an articulated gap cover for pickup tailgate showing our new design;

(52) U.S. Cl. **D12/196**

FIG. 2 is a side elevational view thereof, the elevational view of the opposing side being identical thereto;

(58) Field of Search D12/196, 93, 98;
296/50, 57.1, 26, 26.09, 180.1, 37.6

FIG. 3 is an end elevational view thereof, the elevational view of the opposing end being identical thereto;

(56) **References Cited**

FIG. 4 is a top plan view thereof;

U.S. PATENT DOCUMENTS

FIG. 5 is a bottom plan view thereof; and,

4,443,905 A 4/1984 Kopp
4,531,773 A 7/1985 Smith
4,968,084 A 11/1990 Asher et al.
5,340,184 A 8/1994 Conrado
5,533,771 A 7/1996 Taylor et al.
D374,854 S 10/1996 Little et al.
5,904,391 A 5/1999 Liljenquest et al.

FIG. 6 is a reduced perspective view showing the articulated gap cover for pickup tailgate in use; the broken lines depict environmental structure for illustrative purposes only and form no part of the claimed design.
